UNITED STATES PATENT OFFICE.

HENRY W. A. LEHNERT, OF NEW YORK, N. Y.

CURTAIN-BAR SUPPORT OR THE LIKE.

Application filed December 15, 1924. Serial No. 755,891.

This invention relates generally to the construction of a wall fitting for supporting a curtain bar or the like.

A general object of the invention is to provide a fitting of the type described which can be anchored in position in a wall before the plaster is applied and into which the curtain bar may be removably fitted.

The invention includes a socket member adapted to be anchored in the wall structure as it is formed and to project through the finished wall surface to receive the end of a curtain bar. The construction provides for the removal of the curtain bar from the supporting socket for any purpose.

Other features of the invention will be hereinafter referred to.

In the drawings, in which a preferred embodiment of the invention has been selected for illustration,

Figure 1 is a sectional view showing two wall sections in one of which a curtain bar fitting embodying the invention is shown in section and the other showing a side view of the curtain fitting anchored in place therein.

Figure 2 is a view in combined section and side elevation on an enlarged scale of a rod supporting member embodying the invention.

Figure 3 is a view in end elevation looking from the left of Figure 2.

Figure 4 is a view in end elevation looking from the right of Figure 2.

Figure 5 is a sectional view on an enlarged scale of plaster holding rib members forming part of the invention.

Referring to the drawings for a more detailed description of the invention, in Figure 1 two sections of building wall structure are shown in which wall core members formed of hollow brick or fire-proof blocks 10 are provided with openings 11 in which the fittings comprising the present invention are mounted. The fitting consists essentially of a cylindrical socket member 12 provided at one end with a bridge piece 13 in which is received an adjusting screw 14 that passes through an anchor plate 15 adapted to be enclosed by the cement or

plaster coating 16 which is applied to one surface of the core walls made up of the blocks 10.

The cylindrical member 12 projects outwardly beyond the opposite side of the core wall and is provided with a flange 17 adapted to lie against the face of the core wall

opposite to that to which the plaster coating 16 is applied. In order to insure that the cylindrical socket member 12 is in a properly leveled condition, leveling screws 18 are provided which pass through the flange member 17 and engage the surface of the core blocks 10 so that the flange can be squared or trued with the surface of the core wall.

The outer face of the relatively thin disk-shaped flange member 17 which rests against the surface of the core blocks 10 is provided with rib members 19 having an undercut or keystone-shaped section designed to anchor in place the engaged section of a plaster coat 20 which is applied to the corresponding surface of the core wall as is clearly shown in Figure 1 of the drawing.

Following the application of the plaster coat 20 any desired wall finish may be provided such as tiling 21 in which an opening 22 is provided through which the end of the socket member 12 projects as at 23 in Figure 1 of the drawing.

At the time that the leveling function referred to is produced the socket member 12 may also be rotated with relation to the adjusting screw 14 to cause the socket to be drawn firmly into engaging position with the inner surface of the plaster coat 16 to thereby provide a firm and immovable mounting of the socket in position in the wall structure. The adjustment of the socket member with relation to the adjusting screw 14 is facilitated by the use of lock washers 24 which are interposed between the heads of the adjusting screws 14 and the anchor plates 15.

The inner ends of the socket members 12 are preferably provided with a screw-threaded portion 25 which may be made use of to facilitate the movement of the socket member into and through the opening 11 provided in the core block 10.

The outer end of the socket member 12 is corrugated or scored as at 26 to provide weakened sections to facilitate the cutting off of the end of the projecting socket if the outer end projects more than is desired beyond the outer surface of the finished wall coating.

Another feature of the invention resides in the provision of perforations 27 in the outer end of the socket member 12 for the purpose of locking the curtain rod or bar in the seat provided by the socket member.

For this purpose a corresponding perforation is provided in the curtain bar 28 so that a screw or nail may be inserted through one of the openings 27 in the socket member into the perforation 29 in the rod or bar to thereby lock the bar in place in the socket. In order to cover the exposed end of the socket member 23 when the rod or bar 28 is placed in position therein a sleeve or canopy 30 is placed on the bar and moved up against the surface of the tile or other coating 21 and fixed in position thereagainst by means of the set screw 31 in an obvious manner. It will be apparent that with the construction referred to a curtain supporting device has been provided which is anchored permanently within the structure of the wall itself and which provides for the placing of the curtain rod or bar in position after the construction and painting work has been finished. The removability of the bar which is thus provided is also an advantageous feature in that the bar can be removed in order to refinish the same or to be removed so that it will not interfere with painting or other operations conducted in the room in which it is used.

The adjustability which is provided by the use of the adjusting screw 14 and also the corrugations 26 provide for the use of the socket member 12 in walls of different thickness so that a single standardized size of structure can be used in different situations. While the device has been designed principally for use with fire-proof block partitions shown in the drawing, it can also be used in connection with walls constructed with wood studding by removing the leveling screws 18 and driving screws or nails through the holes thus provided to attach the socket to the studding.

What I claim is:—

1. In a supporting device for curtain bars, a socket member adapted to extend through a perforation in a core element of a wall under construction, an anchoring member attached to the inner end of the socket member by a screw-threaded connection and adapted to be embedded in a plaster coating applied to the adjacent surface of the core element, and the other end of the socket member extending through the finished wall on the other side of the core member to receive an end of the bar.
5. 2. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core member and to be covered by a plaster coating.
- 10 3. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core element and provided with adjusting screws for engaging the core element and thereby leveling the socket member, said flange adapted to be covered by a plaster coating, and the adjacent end of the socket member extending through the plaster coating to receive an end of the bar.
- 15 4. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core member and provided with adjusting screws for engaging the core element and thereby leveling the socket member, said flange adapted to be covered by a plaster coating, and the adjacent end of the socket member extending through the plaster coating to receive an end of the bar.
- 20 5. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core member and provided with adjusting screws for engaging the core element and thereby leveling the socket member, said flange adapted to be covered by a plaster coating, and the adjacent end of the socket member extending through the plaster coating to receive an end of the bar.
- 25 6. In a supporting device for curtain bars, a socket member adapted to extend through a perforation in a core element of a wall under construction, an anchoring member

by a plaster coating, and the adjacent end of the socket member extending through the plaster coating to receive an end of the bar.

70 3. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core element and provided with adjusting screws for engaging the core element and thereby leveling the socket member, said flange adapted to be covered by a plaster coating, and the adjacent end of the socket member extending through the plaster coating to receive an end of the bar.

75 4. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core member and provided with adjusting screws for engaging the core element and thereby leveling the socket member, said flange adapted to be covered by a plaster coating, and the adjacent end of the socket member extending through the plaster coating to receive an end of the bar.

80 5. In a supporting device for curtain bars, a socket member adapted to extend through a perforation in a core element of a wall under construction, an anchoring member attached to the inner end of the socket member and adapted to be embedded in a plaster coating applied to the adjacent surface of the core element, a radially extending flange intermediate the ends of the socket member, said flange adapted to engage the other surface of the core member and provided with adjusting screws for engaging the core element and thereby leveling the socket member, said flange adapted to be covered by a plaster coating, and the adjacent end of the socket member extending through the plaster coating to receive an end of the bar.

85 6. In a supporting device for curtain bars, a socket member adapted to extend through a perforation in a core element of a wall under construction, an anchoring member

attached to the inner end of the socket member and adapted to be embedded in a plaster coating applied to the adjacent surface of the core element, the inner end of the socket member being threaded, a radially extending flange intermediate the ends of the socket member, said flange being adapted to engage the other surface of the core member and provided with adjusting screws for engaging the core element and thereby leveling the socket member, said flange being adapted to be covered by a plaster coating and provided with undercut ribs to hold the plaster in place, said adjacent end of the socket member extending through the plaster coating and provided with perforations for use in anchoring an end of a curtain bar in place in the socket, and a guard member adapted to enclose the bar and cover the end of the socket member.

7. In a supporting device for curtain bars, a socket member having an anchoring member attached to one end by a screw-threaded connection, a radially extending flange intermediate the ends of the socket member and adapted to be attached to an interior wall structure element, and the other end of the socket member being arranged to extend through the finished wall surface to receive an end of the curtain bar.

8. In a structure of the kind described, a wall element having an opening therethrough, a body member extending through the opening, an anchor secured to one end of the body member, and resting against one face of the wall, a member extending laterally from the intermediate portion of the body and engaging the other face of the wall, one of the wall face engaging members being adjustable longitudinally of the body, and the other end of the body being formed with a rod engaging portion.

9. The combination set forth in claim 8, in which the rod engaging portion is a socket.

10. The combination set forth in claim 8, in which the rod engaging portion is a socket having an aperture in its wall.

11. The combination set forth in claim 8, in which the second named wall face engaging member is integral with the body, while the other wall face engaging member is the adjustable one.

12. The combination set forth in claim 8, in which the second named wall face engaging member is integral with the body and is provided with leveling screws.

In testimony whereof I affix my signature.

HENRY W. A. LEHNERT.
